UNITED STATES PATENT OFFICE.

HACKLEY MORRISON, OF RICHMOND, VIRGINIA.

NIPPLE-MAKING MACHINE.

Application filed March 17, 1920. Serial No. 366,662.

To all whom it may concern:

Be it known that I, HACKLEY MORRISON, citizen of the United States, residing at Richmond, in the county of Henrico and State of Virginia, have invented certain new and useful Improvements in Nipple-Making Machines, of which the following is a specification.

This invention relates to automatic machines for simultaneously operating upon both ends of cylindrical metal blanks, and particularly to machines for trimming, reaming, or threading the ends of short sections of pipe used in the manufacture of "nipples".

The general object of the invention is to provide a practical and efficient machine, operating entirely automatically, for trimming or threading the blanks as they are fed down a runway, and for discharging the finished articles into a receptacle.

More specifically, the invention seeks to provide improved feeding mechanism, improved take-off mechanism, novel and effective automatic chucking mechanism, having means to prevent crushing of the blanks, and practical and readily operated means for adjusting the machine to operate on blanks of different lengths.

With the above and other objects in view, the invention consists in the construction, combination and arrangement of parts hereinafter described and claimed, and illustrated in the accompanying drawings, in which:

Fig. 1 is a side elevation of my improved machine;

Fig. 2 is a plan view thereof;

Fig. 3 is a transverse section substantially on the line 3—3 of Figure 2 looking in the direction of the arrow;

Fig. 4 is an elevation looking at the right hand end of the machine;

Fig. 5 is a detail perspective view on an enlarged scale showing a form of tool which I can employ for reaming nipple blanks; and

Fig. 6 is a fragmentary front elevation, parts being in section, showing a modified arrangement of chuck jaws which I sometimes prefer to employ.

Referring to the drawings in detail, the machine comprises a bed plate 1, supported on a suitable body or frame 2. Power is

supplied to the machine by means of a belt 55 working on a set of cone pulleys 3 mounted on a shaft 4, journaled in suitable pedestals 5 secured to the bed of the machine.

In order to simultaneously operate on both ends of the blanks I provide a pair of 60 aligned horizontally disposed tool spindles 6 and 7. These spindles are feathered adjacent their inner ends in sleeves 6^a and 7^a, which are journaled in bearings 8 and 9, respectively carried by working heads 10 65 and 11 which are slidably mounted on the bed 1 of the machine so that they can be moved toward and away from each other. Keyed to the sleeves 6^a and 7^a are gears 12 70 and 13, respectively, which are set into the bearings 8 and 9 as shown.

Feathered on the power shaft 4 are a pair of gears 14 and 15. The gear 15 is disposed in the same plane as and meshes directly with the gear 13, while the gear 14 75 drives the gear 12 through the medium of an intermediate gear 16. By virtue of this arrangement the spindles 6 and 7 are caused to rotate in opposite directions, thus making it possible to thread both ends of a nipple 80 blank properly, and also serving, in great measure, to relieve the chucking device from tortional strains. Instead of toothed gearing, it is obvious that belt gearing may be employed, if desired, belt wheels being 85 feathered on the tool spindles in place of gears 12 and 13, and driven by open and crossed belts from pulleys on the shaft 4, or other countershaft. The gears 14, 15 and 16 are positioned by means of brackets 17 and 18 rigid with the working heads 11 and 10, respectively. It will therefore be seen that all of the gear wheels are constrained to move with the working heads longitudinally of their respective shafts as the working heads are adjusted. The brackets 17 and 18, it will be understood, carry bearings 19 90 and 20 in which the power shaft 4 is journaled.

In order to adjust the working heads toward and from each other, so as to accommodate blanks of varying lengths, the heads 10 and 11 are provided with screw boxes or nuts 21 and 22, respectively, with which engage oppositely screw threaded portions 100 23 and 24 of an adjusting shaft 25, journaled in thrust bearings 26 carried by the bed of the machine, and provided at its

ends with hand wheels 27 by means of which it may be rotated. It is obvious that by turning the shaft 25 by means of one of the hand wheels 27, the working heads 10 and 11 will be caused to move toward or from each other in accordance with the direction of rotation of the shaft 25. The power shaft 4 also carries at one end a bevel gear 28, which meshes with a similar gear 29 fast 10 on a diagonally extending shaft 30 journaled in bearings 31, 32, and carrying at its lower end a worm 33. This worm 33 meshes with a worm wheel 34 fast on a cam shaft 35 extending underneath the bed of the machine longitudinally thereof, and journaled in suitable brackets 36, 37.

The working heads 10 and 11 are formed respectively with extensions carrying depending brackets 38 and 39 provided with 20 lugs 40 and 41, in which are pivotally mounted levers 42 and 43. The lower ends of these levers are preferably off-set, as indicated at 42^a and 43^a, and are provided with anti-friction rollers 44 and 45. These 25 work against cams 46 and 47 feathered on the cam shaft 35 and capable of longitudinal movement thereon, although compelled to rotate therewith. The lower ends of brackets 38 and 39 embrace the shaft 35 and constitute abutments against which the inner 30 ends of the cams 46 and 47 bear. The cams are held in close engagement with such brackets by means of coil springs 48 and 49 secured at one end of the levers 42 and 43, 35 and at the other end of pins 50, 51, set into the brackets 38 and 39. It will be understood that as the high parts of the cams 46 and 47 pass under the rollers 44 and 45, the springs 48 and 49 yield to permit the outward 40 movement of the lower ends of levers 42 and 43.

The upper ends of levers 42 and 43 are bifurcated as shown at 52, 53, and carry circular frames 54, 55, through which the 45 ends of spindles 6 and 7 are free to slide, and are also capable of rotation therein. The frames 54 and 55 are provided with trunnions 56 and 57 mounted in cross heads 56^a and 57^a, mounted to slide in the slotted 50 or bifurcated ends of the levers. In this manner the levers can turn about their pivots without binding or otherwise interfering with the free straight line movement of the tool spindles.

The spindles 6 and 7 carry near their ends 55 collars 60 and 61, respectively, which are adjustable longitudinally of the spindles by means of screw threads 62, 63, or otherwise, and can be set in any position to which they 60 are shifted. Helical springs 58 and 59 surround the spindles 6 and 7 respectively, and are interposed between the adjustable collars 60, 61 and the circular frames 54, 55. These springs act as a cushion through 65 which the movement of the cam operated

levers 42 and 43 is transmitted to the tool spindles, and the object of these cushions is to protect the machine against excessive strains, should the tool fail to properly cut into the blank, or should any abnormal resistance, due to other causes, such as that caused by slight variation in the length of the blanks, be encountered. By means of the adjustable collars, the tension on the springs 58 and 59 may be varied to suit the 75 particular tools with which the tool spindles are equipped.

It will be understood that a variety of different tools may be operated by the spindles 6 and 7. In certain classes of work 80 these spindles may carry drills; in other cases, they could be equipped with cutters of any suitable character; and as shown in the drawings, the spindles carry combined chamfering and reaming tools such as illustrated in detail in Figure 5. These tools are indicated in their entirety by the reference numerals 64 and 65 (see Figure 2), and each preferably consists of an elongated body carrying a plurality of wings. The forward end of each of these wings 65^b (see Figure 5) is cut away to form a notch 65^c, such notch having an inner wall 65^a. The walls 65^a conform more or less closely to the shape of a cone, and are adapted to enter 90 and ream out the inside of a nipple blank, while the outer walls of the notches 65^c, which are of more or less flaring shape, engage over the outside of the nipple blank and smooth off and chamfer the outer edge 100 thereof. While in Fig. 5, I have shown the reaming and chamfering cutters as formed integral, these cutters may be formed of separate removable blades, as embodied, for example, in an improved tool which I have 105 devised, and which forms the subject-matter of my co-pending application, Serial No. 430,866, filed December 15, 1920.

In order to properly hold the blanks in position to be operated on by the tools 110 carried by the spindles, I provide an improved chucking device which forms an important part of my invention. This device consists of fixed and movable members or jaws, adapted to grip the blanks between them. The upper jaw is designated at 66 and is carried by a shank 67, having a screw threaded portion on which works a nut 68. This shank is adjustable vertically through 115 an opening in the middle member 70 of a frame or yoke 71, and is provided at its upper end with a set screw terminating in a wing nut 69. This nut engages on top of the yoke 70, and by manipulating the nuts 68 and 69 it is evident that the chuck member 66 may be adjusted slightly vertically 120 relative to the axis to the tool spindles, thus providing means for compensating slight variations due to wear or grinding of the chuck members.

The yoke or frame 70, 71 is supported by means of four posts 72 set into the bed of the machine and having screw threaded upper ends 73. By means of lock nuts 74 working on the screw threaded ends 73, and arranged one above and one below the yoke, the height of the yoke may be adjusted as desired, thus providing further means for variations in the length of the chuck jaws. The shafts 90 and 91 are journaled in bearings carried by a frame 92, which is pivotally supported at its inner end on a shaft 93 mounted on standards or brackets 93^a. At its outer end the frame 92 has a pin-and-slot connection with a cross-head 94, adjustably supported on threaded posts 94^b. The cross-head is held in adjusted position by means of lock nuts 94^b. To one end of each shaft 90 and 91 is secured a small bevel pinion 95, and these pinions mesh with similar bevel gears 96 fast on a shaft 96^a journaled in portions 96^b of the frame 92. A hand wheel 97 is secured to the end of shaft 96^a, and it will be evident that by turning this hand wheel the shafts 90 and 91 may be caused to rotate synchronously in either direction, thus causing the bars 68 to move toward or away from each other, as required, while remaining always parallel. By this means, the run-way can be readily adjusted to receive blanks of different lengths.

The movable chuck member 78 also has a concave face or seat 77, as clearly shown in Figure 3. This member preferably consists of a pair of parallel elements spaced apart by a shim block 79 (see Figure 1). A bolt 81 passes through the two elements of the chuck member 78, shim block 79, and the bifurcated upper end 80 of a plunger 82. This plunger is capable of reciprocating vertically in a guide or housing 83 depending from the bed of the machine. Also working freely in the housing 83 and disposed below the plunger 82 is a second plunger 85, a stiff short compression spring 84 being interposed between the two plungers within the housing.

The lower end of the plunger 85 carries a roller 86 engaging a cam 87 rigidly secured to the cam shaft 35. It is therefore obvious that as this cam revolves the plungers 85, 82, together with the lower chuck member, will be vertically reciprocated toward and from the fixed chuck member so that the nipple blanks are alternately gripped between the two chuck members and released. The function of the springs 84 is to provide a yielding cushion between the cam operated plunger and plunger 82, so as to prevent crushing of the blank. Owing to slight irregularities in the size of the blanks it would be very difficult to so adjust the chuck members that they would properly hold every blank, if such chuck members were both rigid and unyielding. By virtue of the cushion spring, however, I am enabled to obtain a firm grip on every blank, notwithstanding variations in size, and this without danger of crushing the blank or straining the machine.

In order to feed the cylindrical blanks to the chucking device, I provide an inclined run-way of improved construction. As clearly shown in Figures 2 and 3, this run-way comprises a pair of angle irons 88, or other suitably shaped bars, each of which is provided with a pair of depending ears 89 which engage the threads of a pair of shafts 90 and 91, each shaft having at each side of its center oppositely disposed screw-threads. Supported by each bar 88 is a track member formed of a rod having a transversely inclined upper surface, such as, preferably, a rod 98. These rods are pivoted at their inner ends as indicated at 99 (Figure 3), and their outer ends are preferably bent at right angles, and screw-threaded as indicated at 100. A grooved wing nut 101, engaging the screw-threaded nut 100 and working in an opening in the supporting bar 88, serves to raise or lower the outer end of the rod 98, and thus vary its inclination relative to the supporting bar 88. It will be particularly noted that the rods 98 are carried by the bars 88 in such a manner as to be well spaced vertically therefrom. This is for the purpose of preventing the blanks being clogged by chips or shavings from the tools, as would occur if the run-way consisted of a flat surface. By forming the run-way rails of round or otherwise transversely inclined rods, affording but a single point of contact with the cylindrical blanks, clogging is prevented, as the chips will not accumulate upon such a rod. The rods are spaced above the supporting bars so as to clear any accumulation of chips which may cling to such bars. It has been found in practice that a run-way constructed as described gives the most satisfactory results and never becomes clogged. The vertical portions of the bars 88 which are disposed at the outside of each rod 98, act as guard plates between which the blanks are received, and which serve to guide the blanks as they travel down the run-way, so as to prevent them from falling off. They also serve as a guage to prevent the feeding to the machine of blanks longer than those for which the working heads are set.

In order to remove the finished blanks or articles from the machine and deposit them in a suitable receptacle, I provide

an improved take-off mechanism which also forms an important part of my invention.

Referring especially to Figure 3, this take-off mechanism comprises an inclined table 102, on which is mounted to reciprocate a slide 103, having a depending lug 104 extending through a slot 105 in the table. The lug 104 is connected by means of a link 106 with the upper end of a lever 107 pivoted at 108 and carrying at its lower end a roller 109, engaging a specially shaped cam 110 on the shaft 35. A spring 111 extending between the upper end of a lever 107 and the fixed support serves to cause the roller 109 to follow the cam.

Mounted on the slide 103 is a stripper plate 112 having a bifurcated inner end 113 arranged to straddle or embrace the vertical reciprocable chuck member 78.

The operation of the machine will now be briefly described. Power being supplied as above described, and the working heads 10 and 11 and track rails 98 having been properly adjusted for the particular length of blanks being operated upon, such blanks are caused to roll down the run-way to the chucking device. These blanks may be placed manually at the upper end of the runway, as indicated by X in Figure 3, or they may be fed from a hopper in any suitable or well-known manner. It will be particularly observed that the lower or inner end of the runway is substantially at the level of the upper end of the chuck member 78 when in its lowermost position, as shown in Figure 3. When in this position it is obvious that a cylindrical blank will roll down the run-way and into the concave seat 77 of the chuck member 78. A suitable stop is provided, if necessary, to prevent the blank from rolling off the other side of such chuck member. As the cam 87 turns over the blank will be carried up into engagement with the upper chuck member 66 and firmly gripped between the two chuck members. At this moment the cams 46 and 47 are so timed as to move the tool spindles toward each other, thus bringing the tools simultaneously into engagement with the opposite end of the blank in the chuck. The cam 87 has sufficient "dwell" to hold the blank while the tools are in operation. The chuck member 78 then recedes, carrying with it the finished blank. As the chuck member 78 begins to recede, the cam 110 is so timed as to project the stripper plate 112 into the position shown in Figure 3, and it will be seen therefore that as the chuck member 78 moves downwardly with the finished blank thereon, such blank will engage the bifurcated portion 113 of the stripper plate and be removed or lifted from the chuck member. The finished blank or article thereupon rolls down the inclined stripper plate 112 and table 102 into a suitable box or receptacle

114, while the chuck member 78 continues its downward movement. The stripper plate 112 meanwhile is shifted to the left as viewed in Fig. 3, and remains in such shifted position until the chuck member is about to 70 complete its next upward stroke. Thus the stripper plate does not interfere with the chucking of the blanks. When chuck member 78 reaches its lower-most position another blank automatically rolls into position therein. It will be understood that the run-way is kept full of blanks so that they are continuously crowding downward, so long as they are supplied to the upper end of the runway. Should the supply fail, 80 however, the blanks in the runway will continue to be automatically fed into the chuck until they are all used up, and in this event, the machine may then continue to operate without danger of injury. In all of its positions, except that illustrated in Figure 3, the chuck member 78 serves as a stop against which the lower-most blank of the series bears. The blanks are thus restrained by the chuck member until it reaches the lower 90 limit of its travel, and thereupon a blank automatically falls into position therein. The chuck member acts as a cradle to carry the banks upwardly into position to be engaged by the tools, and as it carries them 95 down again they are removed by the stripper plate, which is projected underneath the blank as the chuck member 78 begins its downward stroke.

While I have thus far described the use of 100 a single chuck jaw at the top and a pair of chuck jaws at the bottom, I desire it to be understood that I contemplate and often prefer reversing this arrangement. This reverse construction is illustrated in Fig. 6, 105 and by reference to this figure, it will be seen that I may provide a pair of upper chuck jaws or elements 66 and 66'. These may be provided with springs such as 76 in Fig. 3 and are held by means of wing nuts 110 or the like 69, 69' in any desired two of a series of openings 70^a formed in the supporting yoke 70'. By this means, a spacing of the chuck elements best suited to the particular length of blanks being operated upon may be readily obtained.

The single lower jaw 77' is carried by a screw threaded standard 78', adjustably received in a threaded socket 82^a of a plunger 82', and secured by means of a lock nut 78^a. 120

In order to prevent accumulations of shavings and the like from clogging the plunger, I preferably provide a shield 78^b, which may be circular as shown, having a central hub threaded on to the standard 78'. 125 This effectually protects the plunger from contact with foreign matter.

It will thus be seen that I have provided a complete automatic nipple manufacturing machine, having many novel and valuable 130

features, and it is thought that the many advantages of the invention will be readily appreciated without further discussion.

What I claim is:—

- 5 1. In a machine of the character described, the combination with a pair of alined tool spindles, of a pair of adjustable working heads in which said spindles are journalled, means for rotating said spindles, 10 means for reciprocating said spindles toward and from each other comprising a pair of levers pivoted on said working heads, a pair of cams arranged to engage and oscillate said levers, means between the adjacent ends 15 of said spindles for supporting blanks to be operated upon, and means for adjusting said working heads and thus varying the distance between the spindle ends so as to operate upon blanks of different lengths, said levers 20 and cams moving together when the working heads are adjusted, whereby a constant relation between them is maintained.
2. In a machine of the character described, the combination with a pair of alined tool spindles, means for rotating and reciprocating said spindles, said means comprising a cam shaft, and a pair of cams rotatable with but slidale on said shaft, means for supporting blanks between the adjacent ends of 25 said spindles, means for adjusting said spindles toward and from each other so as to accommodate blanks of different lengths, and means for simultaneously shifting said cams a corresponding distance along said shaft.
3. In a machine of the character described, the combination with a pair of alined tool spindles, means for rotating and reciprocating said spindles, said means comprising a cam shaft, and a pair of cams rotatable with but slidale on said shaft, a pair of pivoted 30 levers for communicating motion from said cams to said spindles, means for supporting blanks between the adjacent ends of said spindles, means for adjusting said spindles toward and from each other to accommodate blanks of different lengths, and means for simultaneously shifting said cams and the pivot-points of said levers a corresponding amount.
4. In a machine of the character described, the combination with a pair of alined tool spindles, means for rotating and reciprocating said spindles, a pair of working heads in which said spindles are journalled, a cam shaft, cams slidale on said shaft, a pair of levers for communicating motion from said cams to said spindles, said levers being pivoted on said working heads, means for supporting blanks between said working heads, means for adjusting said working heads toward and from each other to accommodate blanks of different lengths, and means for simultaneously shifting said cams a corresponding distance on said shaft, whereby the

relation of said cams to said levers is main- 65 tained constant.

5. In a machine of the character described, the combination with a pair of alined tool spindles, of a pair of working heads in which said spindles are journalled, means for reciprocating said spindles through such journals, means between the working heads for supporting blanks to be operated upon, means for adjusting said working heads toward and from each other to accommodate 70 blanks of different lengths, and means for rotating said tool spindles comprising a power shaft parallel with said spindles, and intermeshing gearing feathered on said power shaft and spindles respectively, all of 75 said gearing being shiftable with said working heads longitudinally of said shaft and spindles.

6. In a machine of the character described, the combination with a pair of alined tool spindles, a pair of working heads in which said spindles are journalled, means for rotating and reciprocating said spindles, means between the adjacent ends of said spindles for supporting blanks to be operated 80 upon, and means for simultaneously adjusting said working heads the same distances toward or away from each other so that blanks of different lengths may be accommodated between the spindle ends, and so that 85 said ends are always equally spaced from the blank supporting means.

7. In a machine of the character described, the combination with a pair of alined tool spindles, of means for rotating and reciprocating said spindles, and means located between the adjacent ends of the spindles for gripping the blanks to be operated upon, said means comprising a pair of chuck members, a rigid frame in which one of said 100 members is supported, cam operated means for moving the other member toward the first to grip a blank between them, said cam-operated member comprising a plunger 105 formed in two sections of the same diameter, arranged in alinement, a stationary guide or housing enclosing said sections, and in which both sections slide, and a spring interposed between said sections within said housing, whereby said chuck member is cushioned, 110 and all the parts protected from foreign matter.

8. In a machine for manufacturing cylindrical articles, the combination with a tool, and means for driving it, of a chuck device for holding the blank in horizontal position adjacent the tool, said chuck device comprising a vertically reciprocable member having a seat in which the finished article rests when released, a stripper mounted to reciprocate in a plane lying between the upper and lower limits of travel of said seat, and means for automatically reciprocating said member 120 125

and stripper in such timed relation that said stripper is moved into a position adjacent said member and below the seat therein when the member is elevated, so that, when 5 said member descends, the finished article resting in said seat is brought into engagement with and deposited upon said stripper.

9. In a machine for manufacturing cylindrical articles, the combination with a tool, 10 and means for driving it, of a chuck device for holding the blank in horizontal position adjacent the tool, said chuck device comprising a vertically reciprocable member having a seat in which the finished article rests when 15 released, a stripper mounted to reciprocate in a plane lying between the upper and lower limits of travel of said seat, said stripper having a bifurcated portion, and means for automatically shifting said 20 stripper and member in timed relation so that the bifurcated portion of the former is caused to straddle the latter at a point below the seat when the seat is in its upper position, whereby, when the said member moves 25 downwardly, the finished article resting in said seat is deposited upon the stripper.

10. In a machine for manufacturing cylindrical articles, the combination with a tool, 30 and means for driving it, of a chuck device for holding the blank in horizontal position adjacent the tool, said chuck device comprising a vertically reciprocable member on which the finished article rests when released, a stripper mounted to reciprocate toward and from said chuck device, and means 35 for automatically reciprocating said member and stripper in such timed relation that said stripper is shifted into a position below and in the path of travel of said article as said member, bearing the article, descends, whereby the article is deposited upon the stripper by the descending chuck member.

11. In a machine for operating on cylindrical blanks, the combination with a horizontal tool spindle, and means for driving it, 45 of a chucking device arranged adjacent thereto for gripping the blanks, said chucking device comprising an upper fixed jaw, and a lower vertically movable jaw, means 50 for reciprocating said lower jaw, an inclined runway down which the blanks roll to the chucking device, the upper end of said movable lower jaw being so shaped as to receive and retain a blank as it moves upward, a 55 stripper plate, and means for automatically projecting the end of said plate into the path of the blank as the lower jaw, carrying the blank moves downward, whereby the blank is removed from the said lower jaw onto the 60 stripper plate.

12. In a machine for operating on cylindrical blanks, the combination with a tool and means for driving it, of a chuck adjacent the tool, and an inclined runway down 65 which the blanks roll to the chuck, said

runway comprising a pair of spaced rods, a frame for supporting the rods, means for varying the inclination of said frame, and means for adjusting the inclination of said rods relative to the frame.

13. In a machine for manufacturing cylindrical articles, the combination with a tool, and means for driving it, of a chuck device for holding the blank in horizontal position adjacent the tool, said chuck device comprising a vertically reciprocable member, an inclined stripper plate disposed adjacent said member and means for automatically shifting said stripper plate into position to engage the ends of the finished 70 article projecting beyond the chuck device and remove the article as the chuck member moves downwardly.

14. In a machine for manufacturing cylindrical articles, the combination with a tool, and means for driving it, of a chuck device for holding the blank in horizontal position adjacent the tool, said chuck device comprising a vertically reciprocable member on which the finished article rests 80 when released, an inclined stripper plate having a bifurcated portion, and means for automatically shifting said stripper plate so that the bifurcated portion thereof is caused to embrace said chuck member and lift the article therefrom as the member moves downwardly.

15. In a machine for manufacturing cylindrical articles, the combination with a tool, and means for driving it, of a chuck device for holding the blank in horizontal position adjacent the tool, said chuck device comprising a vertically reciprocable member on which the finished article rests when released, a stripper plate mounted adjacent 100 said member, and means for automatically projecting said plate into the path of the article as the said member bearing the article moves downwardly, so that the article is thereby transferred from said member to the plate, and thus removed.

16. In a machine for manufacturing cylindrical articles, the combination with a rotary tool, and means for driving it, of a chuck device for holding the blank in horizontal position adjacent the tool, said chuck device comprising a vertically reciprocable member for elevating the blank into position, and on which the finished article rests when released, a stripper plate mounted adjacent said member, means for shifting said stripper plate away from said reciprocable member as the latter moves upwardly with the blank so as to permit the blank to pass, and means for automatically projecting said plate into the path of the article as the said member moves downwardly, so that the article is thereby transferred from the member to the plate, and thus removed.

17. In a machine of the character described, the combination with a horizontal tool spindle, and means for rotating and reciprocating the same, of means located 5 adjacent the end of the spindle for gripping the planks to be operated upon, said means including a pair of chuck members, the upper member comprising a pair of spaced jaws, a rigid frame in which said jaws may be set in various spaced relations, the lower member comprising a single movable jaw, and means for reciprocating said movable jaw toward and from said fixed jaws.

In testimony whereof I affix my signature.

HACKLEY MORRISON.
